UNITED STATES PATENT OFFICE.

WILLIAM G. SCHNEIDER, OF ANDERSON, INDIANA, ASSIGNOR TO GENERAL MOTORS CORPORATION, A CORPORATION OF DELAWARE.

IGNITION COIL.

Application filed October 16, 1924. Serial No. 743,947.

This invention relates to ignition coils for electrical ignition apparatus and includes among its objects to improve the construction of the coil to reduce the cost of manufacture.

Further objects and advantages of the present invention will be apparent from the following description, reference being had to the accompanying drawings, wherein a preferred form of embodiment of the invention is clearly shown.

In the drawings:

Fig. 1 is a plan view of a coil embodying the present invention, the top cover of the coil case being removed;

Fig. 2 is a sectional view on the line 2—2 of Fig. 1;

Figs. 3 and 4 are plan and edge views, respectively, of one of the clamping members for maintaining the core in position;

Fig. 5 is a side view of the coil resistance unit;

Fig. 6 is a sectional view on the line 6—6 of Fig. 5;

Figs. 7 and 8 are side views of the coil core laminations;

Figs. 9 and 10 are views similar to Figs. 1 and 2 showing a modified form of the invention;

Fig. 11 is a plan view of the modified form of lamination shown in Figs. 9 and 10;

Fig. 12 is a plan view of the spacing member in the air gap of the magnetic circuit shown in Fig. 10; and

Figs. 13 and 14 are plan and side views, respectively, of one of the clamping members which secure certain core laminations in position shown in Figs. 9 and 10.

The form of invention shown in Figs. 1 to 10 will first be described. The ignition coil housing includes a non-conducting tube 20, a base 21 and a cover 22. The coil core comprises a bundle of laminations of two different shapes shown at 23 in Fig. 7 and 24 in Fig. 8. These laminations are cut without waste from flat sheet metal. Each rectangle *a*, *b*, *c* and *d* of sheet metal forms two laminations 23 and each rectangle *e*, *f*, *g* and *h* of sheet metal forms two laminations 24. The laminations 23 and 24 are clamped together and are supported by the base 21 by means of two clamping bolts 25, each provided with a nut 26 and cooperating with a clamping plate 27 shown in detail in Figs. 3 and 4. Plate 27 is provided

with holes 28 for receiving the bolts 25 and with a flange 29 adapted to engage the ends of the laminations 24. Plate 27 includes a portion 30 located centrally of the coil tube 20 and provided with a tapped hole 31 for receiving a screw 32 by means of which the cover 22 is secured to the housing tube 20. The primary windings 35 and the secondary windings 36 are assembled upon a non-conducting tube 37 and this coil winding assembly is placed around the branches 23 of laminations 23 before the laminations 24 are assembled. As shown in Fig. 2 the tube 37 is cut away at 38 to receive the laminations 24.

One end 40 of the primary 35 is connected with a terminal 41 for receiving a wire leading to the ignition timer. The other end 42 of the primary 35 and the lead 43 from the inside turn of the secondary 36 is connected with one of the rivets 44 which secures to the tube 20 a bracket 45 which is threadedly engaged by screw 46 for attaching to the bracket 45 a sleeve 47. Sleeve 47 unites in a unit of a metal shield 48, a non-conducting spool 49, a metal terminal 50 and an insulating washer 51. The spool 49 carries a resistance wire 52, one end of which is attached to the metal shield 48 and the other to the terminal 50, therefore the circuit from the rivet 44 to the terminal 50 includes a screw 46, shield 48 and resistance wire 52. The terminal 50 is tapped to receive a screw for attaching to the terminal 50 a wire leading to the ignition switch and then to the battery which is usually grounded in the automobile ignition system.

The lead 60 from the outside turn of the secondary 36 is attached to a hollow rivet 61 which secures to the housing tube 20 a non-conducting sleeve 62 provided with a metal lining 63 which is adapted to receive an insulated flexible conductor provided with a terminal clip which telescopically engages the member 63.

The form of invention shown in Figs. 9 to 14, inclusive, provides space within the coil housing for a condenser 70 having one foil connected by wires 71 with the primary terminal 41 and having the other foil connected by wire 72 with a clip 73 by means of which the condenser is grounded as will be shown hereinafter. In this form of invention the core laminations 23 are reversed, the longer branch extending through the coil

windings and the shorter branch 23^a extending along the outside of the windings. The magnetic circuit is completed by laminations 74 which are cut from sheet metal. As indicated in Fig. 12 the rectangles *k*, *l*, *m* and *n* provide two laminations 74, hence there is no waste in material. The air gap between laminations 74 and 23 is spaced by non-magnetizable spacers 75 shown in Fig. 12.

The laminations 74 and 23 are clamped together and are secured to the base 21 by clamping means which includes a single bolt 76, which divides the laminations as shown in Fig. 9. Bolt 76 extends through an opening 77 in clamping bracket 78 and receives a nut 79 by which the laminations are clamped between the bracket 78 and the base 21. Bracket 78 is provided with ears 80 extending adjacent the outside laminations 74 and prevents spreading of these laminations from the bolts 76. The primary and secondary windings 35^a and 36^a differ in construction from the windings 35 and 36 in that these windings are cylindrical in contour instead of somewhat rectangular and are mounted upon a cylindrical tube 37^a instead of a rectangular one as shown in Fig. 1.

The connections of the terminals of coils 35^a and 36^a are the same as shown in Fig. 1 with the exception that the lead 60^a from the outside turn of the secondary 36^a is connected with a hollow rivet 61^a which secures to the coil case 20 a metallic button 82 provided with a groove 83 for receiving the terminal clip attached to a flexible insulated conductor. It is customary in automobile ignition systems to ground the battery and the ignition coil. Consequently in the form of the invention shown in Figs. 9 and 10 the condenser 70 will be grounded through con-

nections including the terminal clip 73, bolts 76 and base 21.

I claim:

1. An ignition coil comprising, in combination, coil windings, a laminated core including a bundle of U-shaped laminæ extending through and alongside the windings and a bundle of L-shaped laminæ extending across one end of the windings and meeting the branches of the U-shaped laminæ, and means for clamping the laminæ together and to the base, the L-shaped laminæ abutting one branch of the U-shaped laminæ. 45

2. An ignition coil comprising, in combination, coil windings, a core supporting the windings, a coil housing including a tube and a metallic base, metallic means for clamping the core to the base, and a condenser within the housing and having one 55 terminal attached to the core clamping means in order to ground the condenser upon the base. 60

3. An ignition coil comprising, in combination, coil windings, a laminated core supporting the windings and having portions extending exterior to and parallel to the windings, a base, a clamping member having a portion extending transverse to the windings and a portion extending longitudinally thereto, and a bolt extending exteriorly of the windings and parallel thereto, said bolt cooperating with the base with the transverse portion of said clamping member to attach the core to the base, and cooperating with the longitudinally extending portion to bundle together certain of the core laminations. 70 75

In testimony whereof I hereto affix my signature.

WM. G. SCHNEIDER.
